UNITED STATES PATENT OFFICE.

ALBY B. McDOLE, OF BUFFALO, NEW YORK

PAINTING APPARATUS.

1,311,827.

Specification of Letters Patent. Patented July 29, 1919.

Application filed May 5, 1919. Serial No. 294,786.

To all whom it may concern:

Be it known that I, ALBY B. McDOLE, a citizen of the United States, residing at Buffalo, in the county of Erie and State of New York, have invented new and useful Improvements in Painting Apparatus, of which the following is a specification.

This invention relates to painting apparatus of the class comprising a spray nozzle which is moved over the surface to be painted, and a supply tank from which the liquid paint is delivered to the nozzle and which is maintained under air-pressure to expel the paint with the necessary force to form the desired spray.

To obtain the best results, a spray-nozzle having a comparatively small bore is used, but unless the paint is thoroughly mixed and kept free from lumps the nozzle becomes clogged, requiring it to be frequently cleaned and causing delays.

The object of my invention is the provision of effective and reliable means for thoroughly mixing the paint and at the same time effectually breaking up all lumps before they reach the spray-nozzle, in order to insure a steady and uninterrupted discharge of the paint from the nozzle.

In the accompanying drawings:

Figure 1 is a longitudinal section of the apparatus. Fig. 2 is a transverse central section thereof. Fig. 3 is a longitudinal section, on an enlarged scale, of the removable plug carrying the screen. Fig. 4 is a top plan view of said plug and screen.

Similar characters of reference indicate corresponding parts throughout the several views.

1 indicates the paint-supply and mixing tank adapted to contain a quantity of liquid-paint which may be introduced through an opening in the top of the tank normally closed by a screw plug 2. This tank may be of any suitable form, but is preferably cylindrical. Leading to the upper portion of the tank is an inlet pipe 3 for compressed air which is connected with a suitable compressor, not shown in the drawings.

4 indicates the paint discharge pipe communicating with the lower portion of the tank space and extending through a stuffing box 5 in the top of the tank. Connected with the outer end of this pipe is the usual hose terminating in the spray-nozzle 6. This

nozzle forms no part of my invention and may be of any ordinary construction. A shut-off and controlling valve 7 is located in the discharge pipe.

Applied to the open lower end of the discharge pipe is a screen 8 of the proper mesh to intercept lumps or unmixed particles of the paint. This screen may be of any suitable form and construction, but is preferably conical and carried by a removable plug 9 screwed into an opening in the bottom of the tank. This plug has a conical neck or upward extension 10 of skeleton or apertured construction which is encircled by the screen and which is suitably held in place thereon. In its upper end this neck is provided with an opening 11 which receives the open lower end of the discharge pipe 4, which is loosely fitted therein to permit the ready removal of the screen by simply unscrewing the plug 9. The plug has a grooved flange 9^a for receiving a packing gasket 9^b.

Cooperating with the screen, is a suitable mechanical appliance for inducing a current or currents of the liquid-paint against one or more sides of the screen, of sufficient force to break up or disintegrate any lumps intercepted by the screen and to dislodge any arrested particles from its meshes.

The preferred devices for this purpose consist of a pair of rotary propellers 12 secured to a shaft 13 arranged lengthwise in the lower portion of the tank and extending through stuffing boxes in its heads, the shaft being geared to a driving shaft 14. The propellers are located in proximity to opposite sides of the screen and their blades are arranged right and left, or in other words,

the blades of both propellers trend toward the screen, so that although they are turned in the same direction, they produce contrary currents which clash at the screen with the result above described.

While serving to agitate and mix the paint in the tank, these propellers thus perform the important additional function of keeping the mixture free from lumps liable to clog the spraying nozzle 6, thereby maintaining a practically continuous supply of well-mixed paint to the nozzle and, by avoiding interruptions in the work, obtaining the maximum painting capacity of the apparatus.

Should the screen require repair or re-

newal, this can be quickly and conveniently done by removing the plug 9 and without disturbing any other parts of the machine.

I claim as my invention:

- 5 1. A painting apparatus, comprising a pressure-tank adapted to contain liquid paint and having a discharge pipe, a screen applied to the mouth of said pipe, and means independent of the air-pressure in the tank 10 for inducing a current of the paint against the side of said screen.
- 15 2. A painting apparatus, comprising a pressure-tank adapted to contain liquid paint and having a discharge pipe, a screen applied to the mouth of said pipe, and current-inducing devices arranged in the tank adjacent to opposite sides of said screen and both trending toward the same.
- 20 3. A painting apparatus, comprising a pressure-tank adapted to contain liquid paint and having a discharge pipe, a screen applied to the mouth of said pipe, and rotary propellers arranged in the tank on opposite sides of the screen, the blades of both propellers trending toward the screen.
- 25

4. A painting apparatus, comprising a pressure-tank adapted to contain liquid paint and having a discharge pipe, a screen applied to the mouth of said pipe, a rotary shaft arranged in the tank, and propellers 30 mounted on said shaft on opposite sides of said screen, the blades of both propellers trending toward the screen.

5. A painting apparatus, comprising a pressure-tank adapted to contain liquid 35 paint and having a discharge pipe, a plug arranged in the bottom of the tank and provided within the same with an apertured neck communicating with said discharge pipe, and a screen applied to said neck.

6. A painting apparatus, comprising a pressure-tank adapted to contain liquid paint and having a discharge pipe, a removable plug arranged in the bottom of the tank and provided within the same with 45 an apertured neck, said neck having an opening which receives the lower end of said discharge pipe, and a screen encircling said neck.

ALBY B. McDOLE.
